US00D564359S

(12) **United States Design Patent** (10) **Patent No.:** **US D564,359 S**
Trollope et al. (45) **Date of Patent:** **** Mar. 18, 2008**

(54) **BOTTLE**

(75) Inventors: **James D. Trollope**, Frisco, TX (US);
Blair C. Dugger, Frisco, TX (US);
Kendall L. Yorn, Allen, TX (US); **Alan Flude**, London (GB)

(73) Assignee: **Dr Pepper/Seven Up, Inc.**, Plano, TX (US)

(**) Term: **14 Years**

(21) Appl. No.: **29/249,394**

(22) Filed: **Oct. 4, 2006**

(51) **LOC (8) Cl.** **09-01**

(52) **U.S. Cl.** **D9/552; D9/556**

(58) **Field of Classification Search** **D9/682, D9/686, 688-693, 772-776, 516, 520, 537-540, D9/545-547, 549, 550-554, 556-558, 565-567, D9/569; 215/382-384, 396, 398; 220/669, 220/674-675**

See application file for complete search history.

(57) **CLAIM**

The ornamental design for a bottle, as shown and described.

DESCRIPTION

FIG. 1 is a top plan view of a bottle showing our new design; FIG. 2 is a front elevational view thereof; FIG. 3 is a right side elevational view thereof; FIG. 4 is a rear elevational view thereof; and, FIG. 5 is a left side elevational view thereof.

The oblique shade lines shown in the drawings represent that the bottle is transparent.
